JAM CLEAT

Gerard F. Coderre, 524 Matson Hill Road, and
Marcel W. Coderre, 41 Prospect St., both of
Glastonbury, Conn. 06033

Filed Sept. 13, 1966, Ser. No. 3,850

Term of patent 14 years

(Cl. D54—11)

FIG. 1

FIG. 2

FIG. 4

FIG. 5

FIG. 3

FIG. 6

FIG. 7

FIG. 1 is a perspective view of a jam cleat incorporating our novel design.

FIG. 2 is a top plan view thereof.

FIG. 3 is a side elevational view thereof.

FIG. 4 is a rear elevational view of our novel jam cleat.

FIG. 5 is a front elevational view thereof.

FIG. 6 is a perspective view of a modified embodiment of the jam cleat shown in FIG. 1; and

FIG. 7 is a perspective view of still a further embodiment of the jam cleat shown in FIG. 1.

FIGS. 2, 3, 4, and 5 are shown in a reduced scale.

We claim:

The ornamental design for a jam cleat, as shown and described.
